UNITED STATES PATENT OFFICE

2,396,040

SCREW DRIVER

Frank L. Darling, Hollywood, Calif.

Application October 30, 1944, Serial No. 560,962

8 Claims. (Cl. 74—126)

My invention relates to screw drivers of the ratchet type. It particularly has for its objects: to provide a ratchet screw driver with a positive clutch or "lock" whereby the tool may be used as an ordinary screw driver without danger of the clutch slipping; to provide a screw driver with a ratchet drive whose force can be regulated as desired so that any desired torque may be applied to the screw (or nut, if used with a socket wrench end); to provide a tool that, by attaching a socket wrench member to the shaft, the tool may be used as a wrench to tighten nuts with a predetermined force; to provide a tool of a rugged construction, one in which friction is reduced to a minimum and one in which the ratchet mechanism is fully enclosed and protected to prevent tampering; and to provide a tool which can be readily dis-assembled for inspection if desired.

Other objects will in part be obvious and in part be pointed out hereinafter.

To the attainment of the above objects and ends the invention further resides in those novel details of construction, combination and arrangement of parts all of which will be first described in detail and then be specifically pointed out in the appended claims, reference being had to the accompanying drawing in which,

Fig. 1 is a side elevation of the tool.

Fig. 2 is a central longitudinal section of the tool, the screw shaft being shown in elevation.

Fig. 3 is a view similar to Fig. 2, showing the hollow handle and the ratchet sleeve and spring in central longitudinal section and the remaining parts in elevation.

Fig. 4 is a cross section on the line 4—4 of Fig. 3.

Fig. 5 is a cross section on the line 5—5 of Fig. 3 looking in the direction of the arrow.

Fig. 6 is a cross section on the line 5—5 of Fig. 3 looking in a direction opposite that of the arrow.

Fig. 7 is a detail central longitudinal section of a part of the hollow handle or case and the ratchet sleeve mounted therein.

Fig. 8 is a cross section on the line 8—8 of Fig. 2.

In the drawing in which like numerals of reference indicate like parts in all the figures, 1 represents a hollow handle or tubular case, closed at one end and there provided with a bearing 2 for the end 4 of a shaft 3. The shaft 3 has a squared-in-cross-section portion 5 the corners of which are bevelled off, as at 6, to provide bearing surfaces for balls 7.

Longitudinally slidably mounted on and turn-

ing with the shaft 3 is a roller-carriage 16 having two pairs of slots 36 at right angles to one another in which slots rollers 17 are mounted on pins 18. Rotatably mounted on the portion 8, 5 of the shaft below the squared part 5 thereof, is a ratchet wheel 13 having one-way teeth 14 on its periphery and having concave roller-seats 15 on its end face that is opposite that through which the rollers 17 project. The teeth 14 mesh with one-way ratchet teeth 23 on the lower edge of a ratchet sleeve 22 that is longitudinally slidably mounted in the case 1 and is held to turn therewith by means of lugs 25 riveted to the case and riding in slots 24 in the sleeve 22 (see Fig. 7). 10 The sleeve is continuously urged in one direction by a spring 26.

A cylindrical cupped body 11 is fitted on the shaft end 8 and has a sleeve 9 pinned to the shaft as at 10. In the body 11 is tightly fitted a hard 20 metal ball-race disc 12 between which and the ratchet wheel 13 a ball thrust bearing 35 is located.

The open end of the case 1 is provided with clutch teeth receiving recesses 21 to receive the 25 teeth 29 of a shiftable clutch 28 whose sleeve 30 is secured to the sleeve 9 so as to be longitudinally slideable thereon, by a pin 32 which also passes through and secures the shank 37 in the sleeve 9. The sleeve 30 has a slot 31 in which the ends 30 of the pin 32 lie (see Fig. 2). The sleeve 9 has a flat portion forming a recess 33 (Fig. 8) in which a leaf spring 34 is bowed so as to act as a friction device and hold the sleeve 30 in either its operative or its inoperative position.

35 The shank 37 has a squared end 38 with a latch ball 39 of well known construction to receive the working tool attachment's socket 42. This tool attachment may be a socket wrench or a screw driver bit, a screw driver bit 40 being shown 40 for illustration purposes.

The shaft 3 is mounted in the handle 1 and turns with it by means of a screw 41 which turns with the shaft.

A compression spring 19 is mounted on the 45 shaft 3 between the roller carriage 16 and a thrust plate or disc 20 against which plate, and a nut 21 on shaft 3, the spring 19 is located. By turning the nut in one direction the spring can be further compressed and by turning the nut in the 50 opposite direction the spring pressure can be reduced, thus regulating the action of the spring. In this manner the force at which the handle can be turned without turning up the screw being driven may be determined. When it is desired 55 to use the tool as an ordinary screw driver the

clutch member 29 is pushed into engagement with the case 1 thus locking the teeth 29 in the recesses 27.

What I claim is:

1. In a ratchet tool of the class described: a hollow handle-case; a shaft rotatably mounted in said case; a ratchet sleeve mounted in said case to turn with and have longitudinal movement in said case; a body mounted in said case and secured to said shaft to turn with it; a ratchet wheel rotatably mounted on said shaft within said case in cooperative association with said ratchet sleeve; a thrust bearing between said ratchet wheel and said body; a releasable drive connection between said shaft and said ratchet wheel and including force applying means for said drive connections; a tool-carrying shank coupled to said shaft to turn with the same; and a shiftable clutch device for coupling said shaft to said case so the tool may be used as an ordinary screw driver.

2. The tool of claim 1, wherein said releasable drive includes concave seats on said ratchet wheel, a roller-carriage slidably mounted on said shaft to turn therewith, rollers mounted in said carriage to engage said seats, and a compression spring on said shaft and engaging said roller-carriage to press the rollers to their seats.

3. The tool of claim 1, wherein there is provided means for regulating the force of said compression spring.

4. In a tool of the class described: a tubular case having a shaft bearing adjacent one end; a ratchet sleeve mounted in said case to turn therewith and be longitudinally slideable thereon; a ratchet-sleeve-advancing spring in said case and engaging said ratchet sleeve, said ratchet sleeve having one-way clutch teeth; a shaft rotatably mounted in said shaft bearing within the case; a ratchet wheel rotatably mounted on said shaft and having one-way clutch teeth to engage the

teeth of said ratchet sleeve and having roller-receiving seats; said shaft having a squared portion, and a roller-carriage slidably mounted on said squared portion and having rollers to engage said seats; a nut threaded on said shaft; a thrust plate on said shaft and engaged by said nut; a compression spring on said shaft between said thrust plate and said roller-carriage; means for coupling said shaft to a working tool attachment; and means for holding said ratchet wheel in place in said case.

5. The tool of claim 4, wherein bearing balls are provided between said roller-carriage and the portion of said shaft on which said roller-carriage slides.

6. The tool of claim 4, wherein said holding means comprises a cylindrical body within the case and secured to said shaft, and a ball bearing between said cylindrical body and said ratchet wheel.

7. The tool of claim 4, wherein an end of said case has two-way clutch-teeth-receiving recesses, and a sliding clutch member having clutch teeth to enter said recesses and "lock" the case and shaft together, said sliding clutch member being carried on and turning with said shaft and shiftable along the same.

8. The tool of claim 4, wherein bearing balls are provided between said roller-carriage and the portion of the shaft on which it slides; an end of said case having two-way clutch-teeth-receiving recesses; a sliding clutch member having clutch teeth to enter said recesses and "lock" the case and said shaft together, said sliding clutch member being carried on and turning with said shaft and shiftable along the same; said ratchet wheel holding means comprising a body within said case and secured to said shaft, and a ball bearing between said body and said ratchet wheel.
